(57) **CLAIM**

The ornamental design for a food processor base as shown and described.

DESCRIPTION

FIG. 1 is a perspective view of a food processor base comprising a new, original and ornamental design; FIG. 2 is a front elevational view of the food processor base shown in FIG. 1;

FIG. 3 is a right side view of the food processor base shown in FIG. 1;

FIG. 4 is a left side view of the food processor base shown in FIG. 1;

FIG. 5 is a rear elevational view of the food processor base shown in FIG. 1;

FIG. 6 is a top plan view of the food processor base shown in FIG. 1;

FIG. 7 is a bottom plan view of the food processor base shown in FIG. 1; and,

FIG. 8 is an additional perspective view of the food processor base shown in FIG. 1.

The broken lines show portions of the food processor base that form no part of the claimed design.

1 Claim, 8 Drawing Sheets
